UNITED STATES PATENT OFFICE.

GEORGE A. BARTON, OF KANSAS CITY, MISSOURI.

BOTTLE HOLDER.

Application filed April 8, 1923. Serial No. 330,828.

To all whom it may concern:

Be it known that I, GEORGE A. BARTON, a citizen of the United States, and resident of Kansas City, county of Jackson, State of Missouri, have invented a certain new and useful Improvement in Bottle Holders, of which the following is a complete specification.

The present invention relates to devices for holding and locking bottles or the like, with particular reference to a device of this character especially designed for engagement with the necks of milk bottles, for the purpose of securely retaining the same against either casual displacement or deliberate theft, where the bottles are delivered to residences and left in exposed places.

For carrying out this object of the invention, I have devised a simple bottle retaining device adapted to be secured in a convenient location where the bottles are delivered, and automatically operated by the mere insertion of a bottle between the bottle engaging and retaining elements of the device, into securely locked relation with the neck portion of the bottle.

The specific form of the invention herein described comprises a member having a rigid bottle retaining finger, and a movable retaining finger operative by engagement with a bottle into cooperative retaining engagement with the neck portion of the bottle, together with a spring locking device which operates automatically to lock said movable finger in its bottle retaining position.

With the foregoing object in view, the invention will now be described by reference to the accompanying drawing illustrating one form of construction which has been devised for embodying the proposed improvement, after which those features deemed to be novel will be particularly set forth and claimed.

45 In the drawing—

Figure 1 is a perspective view illustrating a device constructed in accordance with the present invention, and with a bottle in retained engagement therewith;

50 Figure 2 is an outer face view of the device, on a larger scale;

Figure 3 is a rear view of the device;

Figure 4 is a plan view of the same; and

55 Figure 5 is a longitudinal sectional view showing the device in open position, with

dotted lines illustrating the movable finger in closed position.

Referring now to the drawing in detail, this illustrates the improved device as comprising a main body or plate portion 7 formed with a plurality of lugs or ears 8 perforated for attaching screws 9, whereby the device may be securely fastened in operative position, as by attachment to the siding or other portion of a building, as illustrated in Figure 1. At one end of the main body or plate portion 7 is formed an outwardly projecting curved bottle retaining finger 10, suitable for engagement with the neck portion of a milk bottle 12, or the like, the drawing illustrating this fixed finger 10 as formed integral with one end of the main plate portion 7. Intermediate its ends the said plate portion 7 is formed with a longitudinal slot 14 for the pivotal mounting of a movable bottle retaining finger 15 which is also of curved outline, and formed with a lug portion 16 intermediate its end, which is received within the slot 14 and pivoted therein upon a vertical pivot pin 17, so as clearly illustrated in Figures 3 and 5.

This construction provides a movable retaining finger 15 having an outwardly projecting portion corresponding to the fixed retaining finger 10, and adapted to cooperate therewith in the retaining engagement with the neck portion of a bottle, as illustrated in Figures 1 and 4. The inner portion of the finger 15, 15', is also adapted to be projected slightly forwardly, when said finger 15 is in open position, as illustrated in Figure 5, in the path of the bottle on its being inserted, whereby the engagement of the bottle with said inner end portion 15' is adapted to move the finger 15 into closed position, as illustrated in Figure 4 and by the dotted lines in Figure 5.

Adjacent to its pivot 17, the lug portion 16 of the movable finger is formed with a lock shoulder 18 adapted for engagement with the lock bolt 19 forming part of a spring lock device 20 which is adapted to be securely housed and protected within a recess 21 formed in one end of the main body or plate portion 7 of the attachment, the key receiving portion 22 of said lock device being accommodated by an opening in the face portion of the plate member 7, so as to present the key hole 23 of the lock in readily accessible position. This lock device

is of any desired practical form, having the lock bolt 19 automatically actuated, as by a spring 24, into locking engagement with the shoulder 18; the shoulder 18 and the latching portion of the bolt 19 are suitably beveled, as illustrated in Figure 5, so that, on swinging of the retaining finger 15 into closed position, the bolt 19 is automatically retracted by the beveled side of the shoulder 18, against the action of the spring 24, to permit movement of the shoulder 18 into position for locking engagement by said bolt 19, as represented by the dotted lines in Figure 5.

From the foregoing it will be apparent that I have devised a practical and efficient device adapted for convenient use for the desired purpose. Preferably, although not necessarily, the device is attached in position above a floor or a shelf 25, as illustrated in Figure 1, and is designed to be left by the housekeeper in open position, as indicated in Figure 5. On delivery of the bottle, the same is simply inserted in between the retaining fingers 10 and 15, which movement engages the neck of the bottle with the portion 15' of the finger 15, thereby swinging said finger into the position illustrated by the dotted lines in Figure 5. This produces interlocking engagement between the shoulder 18 of the finger 15 and the bolt 19 of the lock device 20, so that the bottle is thereby securely locked until released by the use of a key for unlocking the bolt 19, which of course allows the bottle to be easily removed, thereby swinging the finger 15 again into

open position for use in the next bottle delivery.

The improved device is of very simple construction, adapted to be cheaply made, and with practically nothing to get out of order, and its use is adapted not only to prevent the theft of bottles left accessible to vagrant persons, but to prevent any casual displacement of the bottle which would be adapted to break the same or spill the contents, thereof.

What I claim is:

A bottle holding device comprising a main plate portion, a curved retaining finger rigid with said main portion and projecting outwardly therefrom, a curved movable bottle maintaining finger pivoted intermediate its ends to said main plate portion and provided with a lock shoulder adjacent its pivotal point, one end portion of said movable finger being adapted for receiving engagement with the neck of a bottle in cooperation with said rigid finger, the other end portion of said movable finger being operated by the insertion of a bottle between said fingers to swing said movable finger into bottle retaining position, and a spring locking device housed within said main body portion and adapted to spring automatically into locking engagement with the shoulder of said movable finger to hold the latter in bottle retaining position.

In witness whereof I hereunto affix my signature.

GEO. A. BARTON.
